UNITED STATES PATENT OFFICE.

ADOLPH SUNDBECK, OF MINNEAPOLIS, MINNESOTA, ASSIGNOR TO THE PHOTO PLATING COMPANY, OF MINNEAPOLIS, MINNESOTA, A CORPORATION OF SOUTH DAKOTA.

DESIGN FOR A ROCKING TOY.

Application filed March 5, 1927. Serial No. 20,989. Term of patent 3½ years.

To all whom it may concern:

Be it known that I, ADOLPH SUNDBECK, a citizen of the United States, resident of Minneapolis, county of Hennepin, and State of Minnesota, have invented a new, original, and ornamental Design for Rocking Toys, of which the following is a specification, reference being had to the accompanying drawings, forming part thereof.

Figure 1 is a side elevation of a rocking toy, showing my new design; and
Figure 2 is a plan view of the same.

I claim—

The ornamental design for a rocking toy, as shown.

ADOLPH SUNDBECK.
